UNITED STATES PATENT OFFICE.

WILLIAM BARTHOLOMEW, OF CHICAGO, ILLINOIS, ASSIGNOR TO TROY LAUNDRY MACHINERY COMPANY, LIMITED, OF CHICAGO, ILLINOIS, A CORPORATION OF NEW YORK.

CUFF-PRESS.

1,054,269.

Specification of Letters Patent. Patented Feb. 25, 1913.

Application filed September 28, 1911. Serial No. 651,812.

To all whom it may concern:

Be it known that I, WILLIAM BARTHOLOMEW, a citizen of the United States, residing at Chicago, county of Cook, State of Illinois, have invented certain new and useful Improvements in Cuff-Presses, of which the following is a specification, reference being had therein to the accompanying drawing.

10 This invention relates to certain new and useful improvements in cuff presses, the object being to improve the general construction of cuff presses and to provide means for limiting the outward movement of the 15 goods support, said means being capable of being adjusted in order to hold the goods support in the desired position to receive the goods to be pressed.

Another object of the invention is to provide 20 a press in which the pivots or movable joints of the steam and exhaust pipes are in substantially the same horizontal plane with the fulcrum of the goods supporting rod whereby the movements of the joints are 25 decreased, thereby increasing the life of the same and overcoming the difficulties now existing with leaky joints by placing the same below the goods support to prevent any leakage upon the same.

30 A further object of the invention is to provide a press with steam and exhaust connections so arranged that they are out of the way of the operator and at the same time are placed in such position that they 35 may be accessible for the purpose of repairing or adjusting the same.

Other and further objects and advantages of the invention will be hereinafter set forth and the novel features thereof defined 40 by the appended claims.

In the drawings—Figure 1 is a front elevation of my improved cuff press; Fig. 2 is a side elevation of the same; Fig. 3 is a detail vertical section through the supporting 45 rod bearing showing the arrangement of the stops for limiting the outward and inward movement of the same; Fig. 4 is a side elevation; and Fig. 5 is a transverse vertical section through the supporting rod 50 showing the position of the bearing and stops.

Like numerals of reference refer to like parts in the several figures of the drawings.

In the drawings, I have shown a double 55 press in order to permit an alternating

pressing operation of the pressing members and as the pressing and operating mechanisms are exactly alike, a description of one will be sufficient for both. The press comprises a base 1 having a standard 2 provided 60 with pressing heads 3 having the usual form of steam chests and hot shoes 4.

Extending outwardly from the standard 2 is a bracket arm 5 in which is fixed a shaft 6 by set-screws as clearly shown, and upon which are mounted the bearing members 7 which are held in their proper positions thereon by collars 8, said bearing members being provided with vertical bearings 9 in which are mounted to reciprocate 70 the supporting rods 10 having collars 11 adapted to co-act with yielding stops 12. The upper ends of the rods 10 are threaded as shown at 13 upon which are mounted sleeves 14 having oppositely disposed arms 75 15 upon which are mounted base portions 16 of goods supports 17 which are provided with steam chests and padded shoes 18, said supports conforming in shape to the heads 3. The sleeves 14 are adjusted upon the 80 supporting rods 10 by adjusting nuts 19 and the goods supports are secured to the oppositely disposed arms by bolts 20 which facilitates the centering of the supports in order to cause the same to engage the pressing heads in such a manner as to prevent the goods carried thereby from being wrinkled. By this construction the goods supports may be easily and quickly removed 85 from the supporting rods in order to replace the padded shoes or to repair the same. The goods supports are provided with suitable handles 21 in order to allow the same to be drawn outwardly into the position as shown by dotted lines in Fig. 95 2 or to be forced inwardly into vertical alignment with the pressing heads. The bearing members 7 are provided with oppositely disposed lugs 22 at each end, the inner lugs of each bearing member being adapted 100 to co-act with the oppositely disposed stops 23 and 24 carried by a sleeve 25 which is fixed on the shaft 6 and said stops are provided with stop-screws 26 which are engaged by the lugs 22 in order to limit the 105 outward and inward movement of the goods supports and it will be seen that by adjusting the screws, the movement of the goods support may be regulated. This construction enables the press to be adjusted in 110

order to obtain a true vertical alinement of the goods support in respect to the pressing head in order to prevent the goods thereon from being creased or wrinkled when the press is in operation.

In my former Patent No. 1,021,231, March 26, 1912, the swinging movement of the goods support is regulated adjacent its upper end but I have found by experiment that a truer adjustment can be obtained adjacent the fulcrum of the goods supporting rod. It will also be seen that the supporting rod is mounted to the rear of the fulcrum point of the bearing member whereby the tendency of the goods support is to move inwardly.

The supporting rods 10 are provided with yielding connections 27 at their lower ends for connecting the same to the respective operating treadles 28 of a treadle mechanism as shown in my former Patent No. 952,721, granted to me March 22, 1910, said mechanism having the usual releasing treadles 30 and 31 by means of which the treadles 28 are thrown out of operation in order to allow the goods supports to drop and swing outwardly.

In order to improve upon the construction of steam connections for the steam chests of the head and goods support, as shown in my Patent No. 952,721, I provide a main steam supply pipe 32 which has a branch 33 extending to the steam chest of the head which has an exhaust branch pipe 34 extending therefrom having a connection at its lower end with the main exhaust pipe 35. The main steam supply pipe 32 is provided with a movable or pivot joint 36 having a branch 37 which is connected to an exhaust pipe 38 by a movable or pivot joint 39, said pipe 38 having a connection at its upper end with the steam chest of the goods support. Extending from the steam chest of the goods support is an exhaust pipe 40 which has a connection with a branch pipe 41 by a movable or pivot joint 42, said branch pipe 41 having a movable or pivot joint connection 43 with the main exhaust pipe 35. It will be seen that the movable joints connecting the exhaust pipe and steam pipe to the movable goods support are arranged in substantially the same horizontal plane with the fulcrum of the goods supporting rod whereby the swinging movements of the joints are greatly decreased and at the same time a free movement is obtained which allows the goods support to travel in its different movements without being retarded to any extent by the steam connections. It will also be seen that the movable joints are placed below the pressing head and goods support and in such positions in respect to the press--that if any leakage occurs, no damage to the press or goods being pressed results.

The bracket 5 is provided with a bearing 44 in which is slidably mounted a stem 45 of a goods supporting table 46 which is locked in its adjusted position by a setscrew 47 and upon which the goods to be pressed is placed.

From the foregoing description, it will be seen that I have provided a cuff press with an oscillating and reciprocating supporting rod for supporting the goods support in which the movement of the same is limited by stops for obtaining true alinement and the desired position in which the goods support is to be held to receive the goods to be pressed. It will also be seen that the steam and exhaust connections are so formed that the goods supports swing into and out of alinement with the pressing head in such a manner that they can be quickly operated by the treadle mechanism, the movable joints of the connections allowing the goods supports free movement.

Having described my invention and set forth its merits, what I claim and desire to secure by Letters Patent is—

1. In a cuff press, the combination with a pressing head, of a pivotally mounted bearing, a member mounted to reciprocate in said bearing, and stops adapted to be engaged by said bearing for limiting the movement of the bearing.

2. In a cuff press, a standard, a pressing head thereon, a bracket carried by said standard, a shaft mounted in said bracket, a bearing mounted on said shaft, a reciprocating member mounted in said bearing, oppositely disposed lugs carried by said bearing, and a sleeve fixed on said shaft having oppositely disposed stops co-acting with the lugs of said bearing.

3. In a cuff press, a standard, a pressing head thereon, a bracket extending from said standard, a shaft fixed in said bracket, a bearing pivotally mounted upon said shaft having oppositely disposed lugs, said bearing being provided with a vertical bearing, a reciprocating member mounted in said vertical bearing, a goods support adjustably mounted on said reciprocating member, and a sleeve fixed on said shaft having oppositely disposed stops carrying adjustable stop screws adapted to co-act with the lugs of said bearing.

4. In a cuff press, the combination with a standard provided with a pressing head, of a bracket extending from said standard, a shaft fixed upon said bracket, a bearing pivotally mounted upon said shaft, a reciprocating member mounted in said bearing, a goods support adjustably mounted upon said reciprocating member, a treadle mechanism for operating said member, and means for limiting the swinging movement of said bearing.

5. In a cuff press, the combination with

- a standard provided with a pressing head, of a shaft carried by said standard, a bearing pivotally mounted upon said shaft, a reciprocating member mounted in said bearing, a goods support carried by said reciprocating member, a treadle mechanism for operating said reciprocating member, and stops carried by said shaft adapted to be engaged by said bearing for limiting the pivotal movement of the bearing.
6. In a cuff press, the combination with a standard provided with a pressing head, of a pivotally mounted bearing, a reciprocating member movably mounted in said bearing,
- a goods support carried by the upper end of said member, stops arranged to co-act with said pivotally mounted bearing for limiting the movement thereof, and a treadle mechanism having a yielding connection with the lower end of said member for operating the same.

In testimony whereof I affix my signature in presence of two witnesses.

WILLIAM BARTHOLOMEW.
